UNITED STATES PATENT OFFICE

156,569

COVER FOR AN ELECTRONIC TUBE TESTER

Ray Simpson, River Forest, Ill., assignor to Simpson Electric Company, Chicago, Ill., a corporation of Illinois

Application July 17, 1948, Serial No. 147,652

Term of patent 14 years

(Cl. D52—1)

To all whom it may concern:

Be it known that I, Ray Simpson, a citizen of the United States, residing at River Forest, in the county of Cook and State of Illinois, have invented a new, original, and ornamental Design for a Cover for an Electronic Tube Tester, of which the following is a specification, reference being had to the accompanying drawing, forming part thereof.

The figure is a view in perspective of a cover for an electronic tube tester, showing my design.

I claim:

The ornamental design for a cover for an electronic tube tester, as shown.

RAY SIMPSON.
